CLAIM

We claim the ornamental design for a link for rollable television, as shown and described.

DESCRIPTION

FIG. 1 is a top, front and left side perspective view of a link for rollable television, shown in an unfolded configuration; FIG. 2 is a front elevation view thereof; FIG. 3 is a rear elevation view thereof; FIG. 4 is a left side elevation view thereof; FIG. 5 is a right side elevation view thereof; FIG. 6 is a top plan view thereof; FIG. 7 is a bottom plan view thereof; FIG. 8 is a top, front and left side perspective view thereof, shown with a sample environment disclosed in broken lines; FIG. 9 is a top, front and left side perspective view of the link for rollable television, shown in a folded configuration; FIG. 10 is a front elevation view thereof; FIG. 11 is a rear elevation view thereof; FIG. 12 is a left side elevation view thereof; FIG. 13 is a right side elevation view thereof; FIG. 14 is a top plan view thereof; FIG. 15 is a bottom plan view thereof; and, FIG. 16 is a top, front and left side perspective view thereof, shown with a sample environment disclosed in broken lines. The broken lines in FIGS. 6, 7, 14 and 15 depict portions of the link for rollable television in which the design is embodied that form no part of the claimed design. The broken lines in FIGS. 8 and 16 are included for the purpose of illustrating environment and form no part of the claimed design.
